UNITED STATES PATENT OFFICE.

FRED W. COVERT, OF WATERVLIET, NEW YORK, ASSIGNOR TO THE COVERT MANUFACTURING COMPANY, OF SAME PLACE.

DESIGN FOR A HOOK.

SPECIFICATION forming part of Design No. 33,411, dated October 23, 1900.

Application filed September 25, 1900. Serial No. 81,108. Term of patent 14 years.

To all whom it may concern:

Be it known that I, FRED W. COVERT, a citizen of the United States, residing at Watervliet, in the county of Albany and State of New York, have invented and produced a new and original Design for Hooks; and I do hereby declare the following to be a full, clear, and exact description of the same, reference being had to the accompanying drawings, forming a part thereof.

This invention relates to a new and original design for hooks; and it is embodied in the form, arrangement, and configuration represented in the accompanying drawings and hereinafter described.

In the drawings, Figure 1 is a side elevation of the hook, and Fig. 2 is a front edge view.

The shank A terminates at its lower end in an eye B and is somewhat enlarged at its upper end, as shown, at which point the hook portion branches laterally and is curved upwardly and thence forwardly, tapering somewhat, as at C. The end of the hook portion proper lies slightly beyond the plane of the

shank. At the upper end of the shank portion, opposite the lateral extension, is a projection D, having a curved upper wall d and an upwardly-extending side or projection E, located at one side. Through this projection E is an opening, as shown. A depression or notch is formed adjacent the upper inner end of the curved wall.

The essential features of the design, as shown and described, reside more particularly in the upper portion of the hook, including those features representing the hook proper and the outwardly-arranged projection, with its peculiarly-fashioned wall.

Having thus described the invention, what is claimed as new, and desired to be secured by Letters Patent, is—

The design for a hook, substantially as shown and described.

In testimony whereof I affix my signature in presence of two witnesses.

FRED W. COVERT.
